UNITED STATES PATENT OFFICE

2,565,438

FORM CONSTRICTING AND MOLDING GARMENT

Irving Rosner, New York, N. Y., assignor to Even-Pul Foundations, Inc., New York, N. Y., a corporation of New York

Application April 18, 1949, Serial No. 88,191

2 Claims. (Cl. 2-28)

1

This invention relates to form constricting and molding garments, such as a girdle, a brassière, or a combination girdle and brassière.

The principal object of the invention is to provide a garment of the above kind having an improved control panel which secures a maximum lateral distribution of resilient and constrictive effort for the quantity of elastic material employed.

Another object of the invention is to provide a control panel which will provide an excellent local constrictive effect on the body while affording maximum comfort.

A further object of the invention is to provide an improved garment of the above kind which comprises relatively few and simple parts and is economical to manufacture.

The exact nature of the present invention will become apparent from the following description when considered in connection with the accompanying drawings, in which:

Figure 1 is a fragmentary elevational view showing the outside of the front portion of a combined girdle and brassière embodying the present invention;

Figure 2 is a similar view showing the inside of said front portion;

Figure 3 is an outside elevational view of a front control panel for a girdle embodying the present invention;

Figure 4 is an inside elevational view thereof;

Figure 5 is an enlarged horizontal section taken on the line 5-5 of Figure 4;

Figure 6 is a front elevational view looking at the outside of a brassière embodying a front control panel constructed in accordance with the present invention;

Figure 7 is a similar view looking at the inside of the brassière;

Figure 8 is a horizontal section taken on the line 8-8 of Figure 7.

Referring in detail to the drawings and particularly to Figures 1 and 2, 5 indicates a combined brassière and girdle composed of a girdle section 6 and a brassière section 7, respectively having shoulder straps 8 and hose supporters 9. The girdle section 6 has a front control panel 10 comprising an outer layer 11 and an inner layer 12. The outer layer includes a central relatively wide vertically extending area or strip of flexible inelastic material 13 such as plain woven cloth. This area may be cut out centrally of its lower edge to form a notch which is covered by a conventional gusset 14 of porous flexible elastic material. The outer layer also has a narrower ver-

2

tically extending strip 15 of flexible elastic material stitched at one edge to each vertical edge of the inelastic area or strip 13, and a narrow vertically extending strip 16 of flexible inelastic material stitched at one edge to the other or outer edge of each elastic strip 15. The other or outer edges of the strips 16 form the side edges of the outer layer 11. The upper edge of the outer layer 11 is stitched to the lower edge of the front portion of the brassière section 7.

The inner layer 12 likewise includes a wide central vertically extending area or strip of inelastic flexible material 17, narrow intermediate vertically extending areas or strips 18 of flexible elastic material, and narrow side vertically extending areas or strips 19 of inelastic material whose outer edges form the side edges of said inner layer. The layers are of similar width, and each side edge of the inner layer is stitched to the matching or registered side edge of the outer layer. The area or strip 17 is extended above the strips 18 and 19 and stitched at its upper edge to the lower edge of the front portion of the brassière section 7, the lower edge of the inner layer terminating above the lower edge of the outer layer, and the supporters 9 being attached to depending tabs 20 provided on the lower end and at the sides of strip 17. Otherwise, the inner layer is free of connection with the outer layer.

The elastic strips 15 and 18 of the outer and inner layers are of equal widths, and each consists of a minor portion of its layer. Also, said strips are arranged so that each strip 15 overlies a strip 18. However, the strips 15 and 18 are of longitudinally arched form (either angular as shown or curved), and those of one layer face toward each other while those of the other layer face away from each other. For instance, the corresponding ends of the strips 15 in the outer layer diverge, while the corresponding ends of the strips 18 in the inner layer converge. Thus, corresponding ends of each strip 15 and the underlying strip 18 registered therewith cross each other. This provides a wide distribution of the elastic and secures a maximum lateral distribution of resilient and constrictive effort for the quantity of elastic material used.

In Figures 3 to 5 inclusive I show a front control panel for a girdle composed of an outer layer 11a and an inner layer 12a. The outer layer includes a central inelastic strip 13a having the gusset 14a, intermediate arched elastic strips 15a, and side inelastic strips 16a. The inner layer 55 includes a central inelastic strip 17a, intermediate

ate arched elastic strips 18a, and side inelastic strips 19a. The layers 11a and 12a are constructed and joined in substantially the same manner as the layers 11 and 12 of the control panel for the garment of Figures 1 and 2.

In Figures 6 to 8 inclusive, I show a brassière, the front of which has a wide under-breast portion 6b in the form of a control panel constructed in accordance with the present invention. The portion or panel 6b includes an outer layer 11b and an inner layer 12b. The layer 11b includes a central inelastic strip 13b, intermediate arched elastic strips 15b, and side inelastic strips 16b. The inner layer includes a central inelastic strip 17b, intermediate arched elastic strips 18b, and side inelastic strips 19b. The layers 11b and 12b are also constructed and joined in substantially the same manner as the layers 11 and 12. Also, the front of the brassière has side members 21 attached to the side edges thereof, and these members have the usual fasteners to secure the garment about the body, and shoulder straps 8b are attached to these members and to breast cups 22 forming the upper portion of the front of the brassière. The outer layer of the control panel 6b and the strip 17b are stitched at their upper edges to the lower edge of said upper front portion.

In all embodiments, the central strip of the inner layer of the control panel is stitched at its upper edge to the lower edge of the upper front portion of the garment and/or to upper edge of the central strip of the outer layer, and the matched or registered side edges of the layers are stitched together, the layers being otherwise free of connection with each other. Also, in each form, each elastic strip of the outer layer overlies an elastic strip of the inner layer, and the elastic strips are of longitudinally arched form, the elastic strips of one layer facing toward each other and those of the other layer facing away from each other, so that corresponding ends of the registered elastic strips of the layers cross each other to secure maximum lateral distribution of resilient and constrictive effort for the quantity of elastic material used.

From the foregoing description, it is believed that the construction and advantages of the pres-

ent invention will be readily understood by those skilled in the art. Further modifications and changes in details of construction are contemplated, such as fairly fall within the spirit and scope of the invention as claimed.

Having described the invention, what is claimed as new is:

1. A form constricting and molding garment having a front control panel which includes an outer layer and an inner layer of equal widths superimposed on one another, the side edges of the layers being registered and attached to each other at the sides of the garment along the entire length of the inner layer, each of said layers including a vertically extending central area and similar side vertically extending areas of flexible inelastic material, and similar vertically extending areas of flexible elastic material connecting the side areas to opposite sides of the central area, each elastic area of the outer layer being registered with an elastic area of the inner layer, the elastic areas of each layer being of longitudinally and oppositely arched form, the registered elastic areas being oppositely arranged so that the corresponding ends thereof cross each other, the upper edges of the central areas of the layers being stitched together and the layers being otherwise free of connection with each other.

2. The construction defined in claim 1, wherein the elastic areas of the outer layer face away from each other and those of the inner layer face toward each other.

IRVING ROSNER.
